UNITED STATES PATENT OFFICE.

PETER MURRAY, OF EMO, ONTARIO, CANADA.

UNLOADING-MACHINE.

1,245,948.

Specification of Letters Patent.

Patented Nov. 6, 1917.

Application filed December 23, 1915. Serial No. 68,368.

To all whom it may concern:

Be it known that I, PETER MURRAY, of the village of Emo, in the Province of Ontario, Canada, have invented certain new and useful Improvements in Unloading-Machines, of which the following is the specification.

The invention relates to improvements in unloading machines, particularly to a machine for unloading produce from a railway car, and the principal object of the invention is to provide a self propelled machine for quickly and effectively withdrawing grain, coal or similar produce from a car through the doorway opening, the device being arranged so that it can be controlled by a single operator and can be operated to reach all parts of the interior of the car. A further object of the invention is to construct the machine so that it can be readily adjusted to accommodate the various heights of cars which it may have to unload.

With the above and other objects in view which will become more apparent as the description proceeds, the invention consists essentially in the arrangement and construction of parts hereinafter more particularly described and later pointed out in the appended claims, reference being had to the accompanying drawings in which:

Figure 1 represents a side view of the machine as it appears on the track with the conveyer extending directly forward.

Fig. 2 represents a plan view of the machine as it appears when in use, with the conveyer within the car.

Fig. 3 represents an enlarged detailed plan view of the forward end of the machine, the conveyer being removed.

Fig. 4 is an enlarged detailed horizontal sectional view through the machine, the section being taken in the plane denoted by the line X—X' Fig. 1.

Fig. 5 is an enlarged detailed vertical sectional view through the front end of the machine, the section being taken in the plane denoted by the line Y—Y' Fig. 1, and looking rearwardly.

Fig. 6 is an enlarged detailed vertical sectional view through the forward portion of the arm and the sleeve provided on the front shaft and showing the mounting of the connecting bar on the sleeve.

Fig. 7 represents an enlarged detailed vertical sectional view through the arm

supporting bracket at the point where the front shaft passes through the same and showing the wheel threaded on the shaft and its fastening to the bracket.

Fig. 8 is an enlarged detailed vertical sectional view through the front end of the conveyer, the section being taken in the plane denoted by the line Z—Z' Fig. 1 and looking forwardly.

Fig. 9 is an enlarged detailed vertical sectional view through the upper end of the top section of the front shaft.

Fig. 10 is an enlarged detailed vertical sectional view through the coupling connecting the upper and lower sections of the front shaft.

Fig. 11 is an enlarged detailed vertical sectional view through one of the bearings for the square shaft.

Fig. 12 is a plan view of the parts appearing in Fig. 11.

Fig. 13 represents an enlarged detailed vertical sectional view through the machine, the section being taken in the plane denoted by the line T—T' Fig. 1, and looking rearwardly.

In the drawings like characters of reference indicate corresponding parts in each figure.

1 represents the frame of the machine which is rectangular in form and is carried forwardly by traction wheels 2 and rearwardly by carriage wheels 3 located at the ends of the car axles 4 and 5 in the usual way, and forming a car truck. These wheels are flanged in the same manner as ordinary car wheels and are adapted to ride on the standard gaged track rails 6.

On the platform I have mounted an internal combustion engine 7, of any approved type, the engine shaft of which is indicated by the reference numeral 8.

9 is a driving gear wheel mounted on the engine shaft and connected by means of a chain 10 with a counter shaft 11 carried by suitable bearings 12 and 13 mounted forwardly on the frame.

To the rear of this shaft I have located an auxiliary shaft 14 carried by suitable bearings 15 and 16 also secured to the frame.

The shaft 11 is utilized to operate the various parts of the machine as shortly described.

On this shaft I have secured a bevel gear 17 which is designed to drive a pinion 18

60

located at the forward end of a rearwardly directed shaft 19 suitably carried in bearings 20 mounted on the platform and having the rear end fitted with a friction pulley 21 which is designed to engage with one or other of a pair of friction pulleys 22 and 22' mounted on the shaft 14 and connected by a sleeve 23 feathered on the shaft as shown at 24.

10 The ends of the shaft 14 are fitted with worm wheels 25 and 26 which are arranged to mesh continuously with worms 27 and 28 located at the rear ends of driving spindles 29 and 30 suitably suspended from the 15 frame 1 and fitted at their forward ends with further worms 31 and 32 which mesh with worm wheels 33 secured to the front axle 4.

According to the above arrangement it 20 will be seen that by engaging one or other of the pulleys 21, 22 with the pulley 20 the machine can be advanced or backed on the tracks.

25 The sleeve 23 is controlled by a spanning bell crank 34, connected by means of a connecting rod 35 with a conveniently located foot pedal 36 mounted on a forward lower table 37 suitably suspended from the forward end of the frame 1. The foot pedal 30 is arranged within convenient range of the operator's seat indicated at 38.

35 Directly above the table 37 I have provided a second table 39 which is also suitably suspended from the frame 1, and the 35 tables carry an upright center post 40 which extends through the top table and is permanently fastened to the bottom table by means of a flanged coupling 41.

40 42 is a forwardly extending swinging arm pivotally mounted on the lower end of the post 40 and beneath the table 37. This arm is fitted with a toothed segment 43 arranged concentric to the post and designed to mesh continuously with a worm 44 45 mounted on a short worm spindle 45 carried by suitable bearings 46 secured to the underside of the table.

The worm shaft is supplied with a beveled pinion 47 which meshes with a bevel gear 48 mounted on the forward end of a suitably carried driving spindle 49 which has the rear end thereof fitted with a beveled pulley 50 designed to engage with one or other of a pair of oppositely disposed 50 coned pulleys 51 and 52 mounted on the shaft 11 and connected by a sleeve 53 feathered on the shaft as indicated at 53'. The position of the sleeve on the shaft is controlled by a spanning bell crank 54 controlled by a link 55 which passes forwardly to a controlling lever 56 mounted on the front platform and adjacent the operator's seat.

60 From the above it is obvious that the attendant can turn the front arm in any di-

rection by manipulating the hand lever, and that he can retain the arm in any position by moving the coned pulleys 51 and 52 so that neither engages with the pulley 50.

70 The arm 42 extends considerably in advance of the table 37 and has the forward end thereof carried by a bracket 57 which passes upwardly and backwardly to the post in a location above the top table, the rear end thereof being swung on the post.

75 58 is a roller operating on the upper surface of the table 37 and connected by means of a bracket 58' to the arm 42. This roller rides continuously on the table when the arm is turned.

80 The forward end of the arm and the upper portion of the bracket 57 provide bearings for a front driven shaft 59 which is formed from two sections, a stationary top section 59' and a rotatable lower section 59'', the lower section being fastened 85 to the top section by means of a coupling 60.

85 The lower end of the shaft, below the arm, is forked to provide side carrying arms 59^x and 59^y, which carry a conveyer cross shaft 90 61 and on this shaft I mount a pair of chain wheels 62 and 62' and suspend the rear ends of a pair of side bars 63 and 63', the forward ends of which provide bearings for a second conveyer shaft 64 which is fitted 95 with a pair of chain wheels 64' and 64² similar to those 62 and 62'. These front and rear pairs of chain wheels are connected by chains 65 provided at intervals with cross slats 66 on which I mount outstanding 100 scraper plates 67.

105 The above arrangement, when driven, provides an endless conveyer which I utilize for scraping out the produce from the car, as later explained.

110 The nose or forward end of the conveyer is suspended by means of a bail-bar 68 connected by means of an adjusting cable 69 with a winding drum 70 located on the top table and arranged such that it can be rotated for adjusting purposes through the manipulation of a crank 71 disposed on the underside of the platform and within convenient range of the operator. The cable is carried by pulleys 72 and 72' located 115 on the upper ends of the post 40 and the shaft 59.

115 In order that the conveyer may be adjusted to accommodate the various heights of cars, I have made the shaft 59 so that it 120 can be raised or lowered, this being accomplished by threading the upper end thereof and having a wheel 73 threaded on the shaft and fastened to the bracket 57 in such a manner that the wheel will rotate and effect the raising or lowering of the shaft. The manner in which this latter fastening is made is shown in Fig. 7 of the drawings, where it will be noticed that the underside 125 of the wheel is supplied with an extending 130

flange 73^x which is received beneath the fastening plate 73' secured to the bracket. This wheel 73 is connected so that it can be driven by the engine. This is accomplished by passing a cable 74 around the wheel backwardly through suitable guiding pulleys 75 carried by the upper end of the post, then laterally over further guiding pulleys 76 and 76' mounted on the table 10 and finally downwardly to a winding drum 77 mounted on a short shaft 78 carried by suitable hangers 78' suspended from the underside of the top table.

The shaft 78 is driven by means of a beveled pinion 79 which meshes continuously with a bevel wheel 79' located at the forward end of a suitably mounted driving spindle 79^x having the rear end fitted with a coned pulley 79² designed to engage with one or other of a pair of coned pulleys 80 and 80' mounted on the shaft 11 and connected by means of a sleeve 80^x feathered on the shaft as indicated at 80². The sleeve is controlled by a spanning bell crank 81 connected by 25 means of a link 81' with a suitably located lever 82 mounted on the lower table adjacent the seat.

The lower section 59² of the shaft 59 is arranged so that it can be turned to swing 30 the conveyer with respect to the arm. This is accomplished by means of a pulley 83 feathered on the shaft as shown at 83' but free to ride thereon when the said shaft is raised or lowered.

35 The pulley 83 is driven by a continuous cable 84 having the ends extending backwardly through suitable guiding pulleys 85 mounted in the post 40 and having their rear extremities connected to a winding drum 86 carried by a short shaft 87 mounted in suitable standards 87' disposed on the bottom table.

The short shaft 87 is fitted with a bevel pinion 88 which meshes continuously with a bevel wheel 89 located at the forward end of a suitably mounted driving spindle 89^x having the rear end thereof supplied with a coned pulley 89² designed to engage with one or other of a pair of oppositely disposed cone pulleys 90 and 90' mounted on the shaft 11 and connected by a sleeve 91 feathered on the said shaft as indicated at 91'. This sleeve is controlled by a spanning bell crank 92 connected by a connecting rod 92' with a suitably disposed lever 92² mounted on the front platform adjacent the seat.

In order that the conveyer may be driven in all the positions that it may assume, I have provided a square driving shaft 93 immediately to the rear of the shaft 59, which shaft is carried in special bearings provided on the arm and on the bracket 57. These bearings are best shown in Figs. 11 and 12 of the drawings, where it will be observed 65 that the square body of the shaft passes

through a receiving sleeve 93' which is permanently fastened to the shaft and is rotatably mounted in a bearing cup 93² secured to the bracket or the arm, as the case may be.

The lower end of the shaft carries a driving pinion 94 which is slideable on the shaft and is fitted with an extending sleeve rotatably mounted in the connecting bar 94' which passes forwardly and receives rotatably the sleeve 95' of a driving gear wheel 95 rotatably mounted on the lower end of the lower section 59² of the shaft 59. This bar, when the shaft 59 is adjusted vertically, causes the pinion 94 to raise or lower on the square shaft with the gear wheel 95.

To the gear wheel 95 I connect a bevel gear 96 also rotatably mounted on the lower section of the shaft 59 and designed to mesh continuously with a bevel pinion 96' carried by a short spindle 96² extending outwardly 85 from the arm 59.

To the pinion 96' I fasten a chain wheel 97 which drives through a chain 97' a further chain wheel 97² mounted on the adjacent end of the conveyer shaft 61.

The square shaft is driven by means of a pulley 98 mounted on said shaft in a location directly above the rearwardly extending portion of the bracket 57. The pulley 98 is driven by a continuous cable 98' which 95 passes backwardly through suitable guiding pulleys 98² located in the post 40, and then laterally through further guide pulleys 98^x and 98² from which it is directed downwardly to a winding drum 99 carried by a short shaft 99' mounted in suitable standards 99² disposed on the lower table. The latter shaft is driven by a bevel gear 99² which is continuously in mesh with a bevel pinion "a" located at the forward end of a suitably supported driving spindle "b" and the rear end of which is supplied with a cone pulley "c" designed to engage a beveled pulley "d" mounted on a sleeve "f" which is feathered on the shaft 11 as indicated at 110 "g". This sleeve is controlled by means of a spanning bell crank "h" connected by means of a connecting rod "i" with a suitably disposed lever "n" mounted on the lower table adjacent the seat.

The above completes the description of the parts, but in order to better understand the machine I will now describe the manner in which it is operated, assuming that it is desired to unload grain from a car indicated 120 at A and by the machine which is operating on the tracks directly to the side of the car and over a grid B above a grain pit, and adjoining an elevator C.

The machine is brought up to the car, on 125 the tracks, by manipulating the foot pedal 36 which controls the sleeve 23. In any position the machine is brought to a standstill it remains locked in that position, owing to the worm drive. The conveyer is then ad- 130

justed vertically to accommodate the height of the car which it is to unload, and this is done by manipulating the lever 82 which controls the sleeve 80^x. It is obvious that as the wheel 73 is rotated in one direction or the other, it will cause the shaft 59 to raise or lower owing to the fact that the said wheel is held against raising by means of the fastening plate. After the conveyer has been 5 adjusted to the proper height the nose of it is swung into the interior of the car through the car door opening, this being accomplished by operating the lever 92² which controls the sleeve 91. If it is necessary at this 10 time to raise or drop the nose of the conveyer this can be done by manipulating the winding crank 71. The work of sweeping the grain out of the car is then started by throwing in the lever "n" which controls 15 the sleeve "f", to drive the conveyer. When the grain adjacent the door has been swept out by the plates of the conveyer, the grain farther away from the door can be handled by moving up the car, if needs be, and adjusting the swinging arm 42 to admit it into 20 the doorway, and readjusting the conveyer. The position of the arm is controlled by the lever 56 which is directly connected with the sleeve 53. A position such as outlined above, 25 with the end of the arm in the car and the conveyer also within the car, is shown in Fig. 2 of the drawings. According to the arrangement provided, it is possible, by advancing or receding the car and adjusting 30 both the arm and the conveyer, to make the conveyer reach all points in the car.

The grain caught by the plates of the conveyer is swept out through the doorway opening of the car and falls through the 35 grids into the pit.

In cases where the adjustment is made such that the conveyer is passing lengthwise of the car and adjacent one side thereof, I suggest that it would be advisable to insert 40 a board angularly across the car and at the side of the doorway farthest from the rear end of the conveyer. The position of such a board is indicated in Fig. 2 of the drawings, at "p". It will be seen that as the grain is 45 driven back by the conveyer it will be deflected sidewise by the board and out through the door.

Although I have shown special driving connections operated by the engine for working the various parts, still it will be understood that these can be modified in a diversity of ways while accomplishing the same objects, as any of the well known reversible driving connections would operate to equal 55 effect. Such changes would be purely mechanical and would not amount, in the broader sense, to invention.

While the device has been described for unloading grain, still it will be understood

that it can be used for unloading coal or 65 other similar produce.

What I claim as my invention is:—

1. An unloading machine comprising, a truck, a table located at the forward end of the truck, an arm pivotally secured to the 70 table and adapted to swing laterally around its pivot point, a carrying roller operating on the table and secured to the arm, self locking means for turning the arm on its pivot point, an endless conveyer having the 75 inner end thereof pivotally connected to the extending end of the arm, a winding connection adjustably supporting the outer end of the conveyer, means for swinging the conveyer on its pivot point laterally in respect 80 to the arm, said means being operated from the table, and drive means for operating the conveyer in all its adjusted positions.

2. An unloading machine comprising, a truck, a table permanently secured to the 85 forward end of the truck, a forwardly extending, horizontally disposed arm pivotally secured to the table, driving means controlled from the table for turning the arm laterally on its pivot point, a front, vertically 90 disposed sectional shaft carried by the forward end of the arm and having the lower section thereof rotatably mounted and the upper section thereof normally stationary, means operated from the table for turning 95 the lower shaft section, means operated from the table for shifting the upper shaft section endwise to effect the raising and lowering of the lower shaft section, an endless conveyer having the inner end thereof pivotally carried by the lower shaft section, adjustable means operated from the platform and suspending the outer end of the conveyer and means for continuously driving the conveyer 100 in all the adjusted positions of the front 105 shaft.

3. An unloading machine comprising, a truck, an engine mounted on the truck, a stationary front table located at the front end of the truck, an extending arm pivotally secured to the table, driving means actuated by the engine and controlled from the table for swinging the arm on its pivot point and retaining the same in any swung position, a vertically disposed front shaft formed from 110 two sections and having the lower section thereof rotatably mounted in the forward end of the arm and slidable vertically and the lower end of said section forked and the 115 upper end thereof suspended to adjust vertically and coupled to the lower shaft section, means actuated by the engine and controlled from the table for turning the lower shaft section, an endless conveyer having the inner end thereof pivotally suspended from the 120 forked end of the lower shaft section, means for adjustably suspending the outer end of the conveyer, said means being controlled 125

from the table, and means actuated by the engine and controlled from the table for operating the conveyer in all the adjusted positions of the front shaft.

5. An unloading machine comprising, a car truck, an engine mounted on the truck, upper and lower stationary tables located at the front end of the truck, a vertically disposed center post carried by the tables, a forwardly extending arm pivotally mounted on the post, means actuated by the engine and controlled from the lower table for swinging the arm on the post, a supporting bracket having the forward end permanently secured to the forward end of the arm and the rear end pivotally mounted on the upper end of the post, a vertically disposed front shaft formed from two sections coupled together, said shaft having the lower section thereof rotatably mounted in the lower table and the upper section thereof projecting through the bracket and screw threaded, a wheel mounted on the bracket and threaded on the upper shaft section, means actuated by the engine and controlled from the lower platform for turning the wheel to effect the vertical adjustment of the shaft, means actuated by the engine and controlled from the table for rotating the lower section of the shaft, adjusting means controlled from the lower table for supporting the outer end of the conveyer, a vertically disposed square driving shaft rotatably mounted in the bracket and the arm and suspended thereby, a driving connection operated by the engine and controlled from the lower table for rotating the square shaft, a driving gear wheel and a driving bevel gear rotatably mounted on the lower section of the front shaft, a driving pinion slidably mounted on the square shaft and meshing with the driving gear wheel, a connecting bar connecting the gear wheel with the pinion and effecting the sliding of the pinion on the square shaft to accommodate the vertical adjustment of the driving gear with the vertical adjustment of the front shaft and means actuated by the bevel gear for operating the conveyer.
6. An unloading machine comprising, a car truck, an engine mounted on the truck, upper and lower stationary tables located at the front end of the truck, a vertically disposed center post carried by the tables, a forwardly extending arm pivotally mounted on

the post, means actuated by the engine and controlled from the lower table for swinging the arm on the post, a supporting bracket having the forward end permanently secured to the forward end of the arm and the rear end pivotally mounted on the upper end of the post, a vertically disposed front shaft formed from two sections coupled together, said shaft having the lower section thereof rotatably mounted in the lower table and the upper section thereof projecting through the bracket and screw threaded, a wheel mounted on the bracket and threaded on the upper shaft section, means actuated by the engine and controlled from the lower platform for turning the wheel to effect the vertical adjustment of the shaft, means actuated by the engine and controlled from the table for rotating the lower section of the shaft, adjusting means controlled from the lower table for supporting the outer end of the conveyer, a vertically disposed square driving shaft rotatably mounted in the bracket and the arm and suspended thereby, a driving connection operated by the engine and controlled from the lower table for rotating the square shaft, a driving gear wheel and a driving bevel gear rotatably mounted on the lower section of the front shaft, a driving pinion slidably mounted on the square shaft and meshing with the driving gear wheel, a connecting bar connecting the gear wheel with the pinion and effecting the sliding of the pinion on the square shaft to accommodate the vertical adjustment of the driving gear with the vertical adjustment of the front shaft and means actuated by the bevel gear for operating the conveyer.

Signed at Winnipeg, this 22 day of November, 1915.

PETER MURRAY.
